UNITED STATES PATENT OFFICE

ROBERT B. SCHINDLER, OF SPRING CITY, PENNSYLVANIA, ASSIGNOR TO SCHUYLKILL VALLEY MILLS, INC., OF SPRING CITY, PENNSYLVANIA

DESIGN FOR A STOCKING

Application filed April 13, 1932. Serial No. 43,484. Term of patent 3½ years.

To all whom it may concern:

Be it known that I, ROBERT B. SCHINDLER, a citizen of the United States, residing at Spring City, county of Chester and State of Pennsylvania, have invented a new, original, and ornamental Design for Stockings, of which the following is a specification, reference being had to the accompanying drawing, forming part thereof.

showing the design of fabric on a reduced scale, the design extending from the toe of the stocking to the welt thereof.

Figure 2 is a fragmentary view of the leg of the stocking showing the fabric, actual size.

I claim:

The ornamental design for a stocking as shown and described.

ROBERT B. SCHINDLER.
